CHAIR

Arthur C. Ferro, Creve Coeur, Mo., assignor to Contour Chair-Lounge Co., Inc., St. Louis, Mo., a corporation of Missouri

Filed Aug. 12, 1965, Ser. No. 86,553

Term of patent 14 years

(Cl. D15—11)

The dominant features of my design reside in the shape and configuration of the headrest and in those portions shown in full lines on the drawing.

I claim:

The ornamental design for a chair, as shown and described.
